UNITED STATES PATENT OFFICE.

EDWARD LAWSON FENERTY, OF HALIFAX, NOVA SCOTIA, CANADA.

SHOVEL.

SPECIFICATION forming part of Letters Patent No. 398,887, dated March 5, 1889.

Application filed September 18, 1888. Serial No. 285,690. (No model.) Patented in Canada, September 24, 1886, No. 25,002.

To all whom it may concern:

Be it known that I, EDWARD LAWSON FENERTY, of Halifax, in the Province of Nova Scotia, Dominion of Canada, have invented a 5 certain new and useful Improvement in Shovels, (for which I have obtained Letters Patent in the Dominion of Canada, September 24, 1886, No. 25,002,) of which the following is a description sufficiently full, clear, and 10 exact to enable any person skilled in the art or science to which said invention appertains to make and use the same, reference being had to the accompanying drawings, forming part of this specification, in which—

15 Figure 1 is an isometrical perspective view of my improved shovel, the handle being removed; Fig. 2, a vertical longitudinal section of the same, the handle being shown as broken off; and Fig. 3, a vertical transverse section 20 taken on line $x-x$ in Fig. 1.

Like letters and figures of reference indicate corresponding parts in the different figures of the drawings.

My invention relates to that class of shovels which are known as "socket-shovels;" and 25 it consists in certain novel features, as hereinafter fully set forth and claimed, the object being to produce a simpler, cheaper, and more durable article of this character than is now 30 in ordinary use.

The nature and operation of the improvement will be readily understood by all conversant with such matters from the following explanation.

35 In the drawings, A represents the body or pan of the shovel, B the handle, and C the socket.

The pan A may be constructed in any desired form.

40 The socket C consists of a circular metallic tube, bent on a slight curve at m to afford greater leverage in using the shovel. The upper end or mouth of the socket C has its inner edge beveled, as shown at t in Fig. 2, to 45 enable the handle to be more readily inserted therein, and making a flush joint therewith instead of a square joint, as in shovels of ordinary construction, and thus lessening the liability of the handle to break at this point.

50 One side of the lower end of the socket is

extended, forming a tang or flange, f , by which it is secured centrally to the under side of the heel of the body A by rivets z .

A covering-plate, D, consisting of a curved piece of metal of suitable shape to cover the opening at the lower end of the socket, is secured at its point and sides to the pan A by rivets z , and has its upper end secured to the inner face of the socket by rivets v . This arrangement of the parts is found to greatly 55 strengthen the shovel, and as the rivets v and plate D are within the curve on the under side of the shovel very little wear comes upon them, and the shovel lasts far longer than when constructed in the ordinary manner. 60

It will readily be seen that it is necessary for the rivets v z to become entirely cut through before the neck or socket C can become loosened from the pan.

Instead of riveting the covering-plate D to 70 the pan A and socket C it may be welded on, if desired, the particular advantage of said plate, in addition to covering the hole in the foot of the socket C, being to brace the shovel and prevent said socket from being easily detached or loosened thereon.

Having thus explained my invention, what I claim is—

1. In a shovel, the combination of a body or pan, a curved socket riveted to said pan and 80 having the inner edge of its mouth beveled, a handle, and a covering-plate riveted to said pan and the inner side of said socket, substantially as set forth.

2. In a shovel, a covering-plate, as D, secured to the pan and inner side of the socket of said shovel, substantially as and for the purpose set forth.

3. In a shovel, the combination of the pan A, the socket C, provided with the beveled 90 mouth t and tang f , and secured to said pan by rivets z , the covering-plate D, secured to said pan and the inner side of said socket by rivets v z , and the handle B, all being arranged substantially as described.

EDWARD LAWSON FENERTY.
